CHAIR CONVERTIBLE TO IRONING BOARD

Robert Charles Lightbourne, Birmingham,
EnglandApplication September 26, 1949, Serial No. 117,873
In Great Britain September 27, 1948

5 Claims. (Cl. 155—43)

1

This invention relates to kitchen furniture. An article of furniture is provided which can be adapted to be used as a chair, an ironing board, and preferably also steps, of the type comprising a frame on which is pivotally mounted a member formed of two panels or members arranged at an angle to one another and substantially in T-shaped formation, which member is mounted to be turned into position with either panel or member horizontal or substantially horizontal to constitute either an ironing board or a seat or platform at the top of the frame with the ironing board panel forming a back to the seat or platform. An object of the invention is to provide a simplified construction in which the combined seat and ironing board are rigidly fixed in either position for use. A further object is to enable the structure to be quickly adjusted for its particular use. By the present improvements also a catch arm is pivotally mounted on the combined seat and ironing board and is adapted to automatically catch engage the frame or parts thereon in either position of the seat and ironing board, so that a rigid structure is obtained when the article is used either as a seat or an ironing board. The arm is adapted to engage a catch on the base frame and be spring-urged into the catch position, and the arrangement is such that when the catch arm is released to permit of the pivotal movement of the combined seat and board from one position to another, the catch will ride into position for automatically engaging the catch to hold the combined seat and board in the position to which it has been moved. According to a further feature, the base frame on which the ironing board and seat is pivotally mounted is of a simplified construction, and comprises two side frames comprising tubes and a top bracket to which tubes are fixed, the brackets forming a support for the seat.

Referring to the drawings:

Figure 1 is a side elevation of a device constructed according to this invention, showing the ironing board in position for use, and indicating in dotted lines the position of the parts for use as a seat or steps.

Figure 2 is a rear view.

Figure 3 is an inside face view of the frame bracket.

Figure 4 is an end elevation of the bracket shown by Figure 2, and

Figure 5 is an elevation of a catch arm.

According to a convenient embodiment of this invention, the base structure comprises two side frames each formed of two outwardly and down-

2

wardly inclined or splayed tubes 1 which are connected near the bottom by a cross tube 2, and the tops of the inclined tubes 1 are connected to a top bracket 3 comprising an aluminum casting. The tubes 1 of the side frames are connected by the tube 2a, so that the frames and tube 2a constitute a base frame. The inside face of this top bracket 3 has recesses 4, and the outer inclined sides of the inclined tubes bear against the outer inclined sides of the recesses, and the tubes are fixed in position by means of bolts 5 which are passed through the tubes and the bracket 3. The two side frames are stayed apart at the front by means of steps which comprise angle brackets 6 which are pinned or bolted to the front inclined tubes 1, and such brackets are pinned to the treads 7 of the steps which treads are flanged metal plates. A seat member 8 is pivotally mounted on the brackets 3 so that it can be pivoted into position with the underside of the seat resting on abutment faces 3a on the tops of the brackets 3 or into an upright position at the front of the frame with the underside of the seat bearing against abutment faces 3b at the front ends of the brackets 3 as shown by Figure 1. The seat has an ironing board 10 fixed thereto intermediate its length and at a suitable angle by means of a gusset 11, so that one portion of the ironing board forms an inclined back for the seat. The seat 8 comprises a cast aluminum base as shown by Figure 2 having ribs 8a and 8b and the gusset 11 which is U-shaped in cross section and fits over the rib 8a. When the seat is pivoted upwardly, the ironing board is arranged horizontally at a height equal to the height of the frame and the height of the raised seat. The ironing board 10 is covered by a flanged plate fixed by pins passing through the flanges into the board. The front end of the underside of the seat 8 has lugs 9 formed on the said ribs 8b on the underside and such lugs have trunnion pins 9a thereon to pivotally engage recesses 3c in the inner faces of the top brackets 3 to pivotally mount the seat, and when the seat is raised to bring the ironing board, fixed on the back of the seat, into the raised position, the seat bears against the front edges of the top brackets 3. In order to lock the seat in the raised or lowered position, arms 11 are fixed on pins 13a pivotally mounted on lugs 12 on the underside of the seat 8, and such arms are spring pressed inwardly and downwardly towards the underside of the seat, conveniently, by means of mouse-trap springs 13 on the pivot pins 13a carrying the arms 11. One end of each mouse-trap helical

spring is anchored at one end to a pivot pin 13a and at the other end to a lug 12. The arm 11 is curved inwardly and a notch 14 is formed in the edge at the inner side of the arm near the outer end, and this notch, when the seat is lowered, registers with a pin 15 projecting inwardly from a front tube of the said frame, and the spring holds the arm in position with the notch engaging the pin. The notch may be slightly wedge-shaped and the pin is correspondingly wedge-shaped in cross-section, so that the pin fits the slot without loose play, to thus rigidly hold the seat bedded on the top brackets 3 of the side frame. A corresponding projection 15a is formed on the inner side of the top bracket 3, and when the seat is raised to position the ironing board, the arm is moved into position to spring engage the pin 15a and thus lock the parts in the raised position. Two arms 11 are provided and connected by a cross tube 16, and such two arms engage pins 15 and 15a on each side of the structure. When the seat is lowered, the cross tube 16 is depressed to release the arms 11 from the catch pins 15, enabling the seat to be raised which will move the arms rearwardly and upwardly into position to automatically engage the said pins 15a on the top brackets, the arms 11 riding on the pins 15a from one position to the other. To return the seat in the lowered position, the said cross bar is pulled rearwardly leaving the seat free to be lowered, when the arms will ride forwardly to automatically engage the said projections on the front legs. Preferably, the component parts of the structure are detachable, so that the structure can be packed into a small space which is convenient for transport. This frame structure is simple in construction and cheap to manufacture.

Having thus described the invention, what is claimed as new and desired to be secured by Letters Patent, is:

1. An article of furniture comprising a base frame formed of two connected side frames each comprising outwardly and downwardly splayed tubes and a top bracket to which the upper ends of the tubes are fixed, a structure formed of two members constituting respectively a seat and an ironing board arranged at an angle to one another and with the seat pivoted on said top brackets so that it can be turned into position with either the seat or ironing board in a horizontal position, abutment faces on the top and front ends of the said brackets against one of which said seat is supported when in either position, and a catch device for holding the said structure constituting the combined seat and ironing board in either position.

2. An article of furniture comprising a base frame formed of two connected side frames each comprising outwardly and downwardly splayed tubes and a top bracket to which the upper ends of the tubes are fixed, a structure formed of two members constituting respectively a seat and an ironing board arranged at an angle to one another and with the seat pivoted on said top brackets so that it can be turned into position with either the seat or ironing board in a horizontal position, abutment faces respectively on the top and the front ends of the said brackets against which said seat is supported when in either position, and a catch device for holding the said member constituting the combined seat

and ironing board in either position and steps on the said tubes of the base frame.

3. An article of furniture comprising a base frame, a structure formed of two members constituting respectively a seat and an ironing board arranged at an angle to one another with the seat member pivotally mounted on said base frame, so that it can be turned into position with either the seat or ironing board in a horizontal position, spaced brackets on the top of the base frame with the seat bearing respectively against horizontal top or vertical front abutment faces on said brackets, and a catch arm pivotally mounted on the said structure, catch pins on the base and spring means for engaging the catch arm on a said catch pin in either position of the seat and ironing board.

4. An article of furniture comprising a base frame, a structure formed of two members constituting respectively a seat and an ironing board arranged at an angle to one another with the seat member pivotally mounted on said base frame, so that it can be turned into position with either the seat or ironing board in a horizontal position, spaced brackets on the top of the base frame with the seat bearing respectively against horizontal top or vertical front abutment faces on said brackets, a catch arm pivotally mounted on the said structure constituting the seat and ironing board, a catch pin on the said frame which is engaged by a notch in the edge of the catch arm to hold the ironing board in a horizontal position, a second catch pin on the said base frame which is engaged by the said notch in the catch arm to hold the seat in a horizontal position, and spring means for urging the catch arm into engagement with the said catch pins.

5. An article of furniture comprising a base frame, a structure formed of two members constituting respectively a seat and an ironing board arranged at an angle to one another with the seat member pivotally mounted on said base frame, so that it can be turned into position with either the seat or ironing board in a horizontal position, spaced brackets on the top of the base frame with the seat bearing respectively against horizontal top or vertical front abutment faces on said brackets, a catch arm pivotally mounted on the underside of the seat portion of said structure constituting the seat and ironing board and having a notch in the edge of the outer end of the arm, a catch projection on the said base frame adapted to be engaged by said notch when the ironing board is horizontal, spring means urging the arm against said projection, the said arm being shaped and arranged to slide against the rear side of the projection when the ironing board is moved into an upright position, and a second catch projection on said frame which is automatically engaged by the said slot in the catch arm by the action of said spring means when the ironing board is moved into an upright position.
